UNITED STATES PATENT OFFICE.

CHARLES DAVID HAVENSTRITE, OF NEWARK, NEW JERSEY.

AMUSEMENT APPARATUS.

No. 800,297.

Specification of Letters Patent.

Patented Sept. 26, 1905.

Application filed December 5, 1904. Serial No. 235,589.

To all whom it may concern:

Be it known that I, CHARLES DAVID HAVENSTRITE, a citizen of the United States, and a resident of Newark, in the county of Essex and State of New Jersey, have invented certain new and useful Improvements in Amusement Apparatus, of which the following is a specification.

This invention relates to an amusement apparatus for producing illusory effects; and its organization comprises a vehicle and the like which normally remains in one place while the senses of the occupants thereof are subjected to effects that would be produced were the vehicle propelled through various temperatures, scenes, smooth or rough roads, and the like.

In the accompanying drawings the invention is shown with an automobile in a building, although any other vehicle, boat, and the like might be employed.

Figure 1 represents a vertical longitudinal section of a building with the invention partly in section. Fig. 2 shows a partial top view of Fig. 1. Fig. 3 is a partial enlarged top view of the running-gear of the invention, and Fig. 4 represents an elevation of Fig. 3 with a vehicle in position.

Referring particularly to Figs. 1 and 2, a building is shown at A with the entrance-opening A' and exit-opening A''. The platform B of a turn-table supports the automobile C, and the latter is held in place on wheels S¹⁵ S⁶ with the chain C². An engine D is geared with a compressor E and a blower F. A boiler G supplies steam to said engine and to the steam-coil H, which latter is placed within the heater-tank H'. A compressor E is connected with the cooling-coil I, placed within the cooling-tank I'. Piping K, with valves K' to K'', extends from the blower F and connects with the heater and cooling-tanks. The piping K runs along the top of the building to the rear thereof, where it terminates in a nozzle K⁷. Piping L runs from an opening in the floor of the building to and through the front wall thereof. A kinetoscope M or picture-machine is supported in the front of the building for projecting pictures on the movable screen M'. Electric lights N are controlled from a panel-board N'. The shaft d of the engine carries a pulley d², which is belted with a pulley d³ on the intermediate shaft d⁴, and the latter shaft d⁵ is belted, by means of the belt d⁵, to the shaft d⁶, which carries the bevel-gear d⁷, that meshes

with the gear d⁸ on the vertical shaft d⁹. A screen O is carried and driven by the shaft d⁹, turning with the same and extending around the shaft d¹⁰ at the side of the building. A horizontal shaft d¹¹ carries a bevel-wheel d¹², that meshes with a bevel-wheel d¹³, supported at the upper portion of the shaft d⁹. The shaft d¹¹ carries and drives a screen O', which returns over a shaft d¹⁴, and the said shaft d¹¹ carries a bevel-wheel d¹⁴, that meshes with the gear d¹⁵, secured to the shaft d¹⁶, which latter carries and drives the screen O², which returns over the shaft d¹⁷. The engine D is connected by the belt D' with the shaft P, that carries the bevel-wheel P', which latter meshes with the bevel-wheel P² of the shaft P³.

Referring now to Figs. 1, 3, and 4, the shaft P³ carries a bevel-gear P⁴, that meshes with the bevel-gear P⁵, secured to the vertical shaft P⁶. The latter shaft carries a clutch P⁷, turns in a bearing P⁸, and has secured at its upper end the pinion P⁹, that meshes with the spur-gear Q', that constitutes the bed-plate of the turn-table Q. The spur-gear Q' has fixed to it plates Q², to which latter are fastened the journal-brackets Q³, that support the rollers Q⁴, and the said rollers are arranged to run on tracks Q⁵. The clutch P⁷ has extending from it the lever R, fulcrumed in a bearing R', and the other end of the said lever is pinned to a sleeve R², the upper end of which has pinned to it the bell-crank R³, with the handle R⁴. The crank R³ is journaled in a bearing R⁵. The shaft P³ carries the bevel-gear R⁶, that meshes with the bevel-gear R⁷, supported on the vertical shaft R⁸. At the upper end of the latter shaft is secured the bevel-wheel R⁹. A line of shafting S in two portions is journaled under the platform of the turn-table, the said portions being connected by the clutch S², a bevel-wheel S³ on one of said portions meshing with the bevel-wheel R⁶ and a bevel-wheel S⁴ on the other portion meshing with the bevel-wheel S⁴ on the axle S⁵, which latter carries the driver-wheels S⁶. On the shaft S⁵ is fastened a sprocket-chain wheel S⁷, which by means of a chain S⁸ is geared with the chain-wheel S⁹, carried on the shaft S¹⁰ of the second pair of driver-wheels S⁶. The wheels S⁶ are generally made with projections S¹¹ and depressions S¹² on their circumferential surfaces, and the axles S⁵ and S¹⁰ are supported in journal-bearings S¹³, that are carried on a plate Q⁶, fastened to the top of the spur-gear Q'. Adjacent to the driver-wheels S⁶ are journaled

similar wheels S^{15} on the axles $S^{16} S^{17}$. Each pair of wheels, like $S^6 S^{15}$, form supports for the wheels C^3 of the automobile C. On the axles $S^{16} S^5 S^{17} S^{10}$ are mounted the brake-wheels T, that are provided with the brake-straps T', which latter extend from the brake-beams T². The said brake-beams are journaled on pins T³, carried in brackets T⁴, extending up from the plate Q⁶. The said brake-beams overlap each other at their free ends, as shown at T⁵. Springs T⁶ extend between the plate Q⁶ and the beams T², and a screw U, with hand-wheel U', turns in a screw-bracket U² and has a collar U³, which bears up against a bearing U⁴. From the clutch S² extends a lever X, which is fulcrumed on a pin X', and the other end of the lever X is connected with a vertical lever X², that is journaled in a bracket X³.

To operate the invention, the automobile is run on the turn-table, the guide-rails C⁴ insuring its proper position on the tracks C' of the table and upon the wheels $S^{15} S^6$. Then after the building is closed with doors at the openings (not shown) a warm-air blast is produced by the blower driving the air through the tank H', keeping the valves K² K³ K⁴ open and the valves K', K⁵, and K⁶ closed, allowing the air to leave the funnel K⁷ and striking any occupants of the automobile. The air leaves by means of the pipe L, securing ventilation in addition to the blast. If a cold-air blast is required, the blower F forces air through the tank I' and piping K, by closing the valves K² K³ K⁴ and keeping the valves K', K⁵, and K⁶ open. The electric lights N, by means of the panel-board N', are made to produce different illuminating effects. The kinetoscope M is used to throw various pictures on the screen M', which latter can be raised out of the way should it be desired to run the automobile out of the exit A². The side screens O and O² and the upper screen O' are driven by means of the engine D and the connections between said engine and the shafts d⁹, d¹¹, and d¹⁶. The driver-wheels S⁶ are driven by the engine through the shaft P³ and its connections, and the movements of said wheels are controlled by the clutch S² and the brake-bands T', with their connections. When it is desired to run the said wheels, the hand-wheel U' is turned to allow the springs T⁶ to raise the brake-beams T², when the bands T' will be raised from the brake-wheels T and the clutch S² is put into gear by means of the lever X². The wheels S⁶ by turning will turn the wheels C³ of the automobile, and by reason of the uneven surfaces on said wheels will produce the effect of running on an uneven road. If it is desired to stop the rotation of the wheels C³, the clutch S² is thrown out of gear and the brake-bands T' are set upon the wheels T by means of the hand-wheel U'. Should it now be desired to turn the turn-table, the latch W is thrown out of engage-

ment with its stop W' and the clutch P⁷ is thrown in gear by means of the levers R and bell-crank R³, by virtue of which rotation will be transmitted from the shaft P³ to the shaft P⁶, which will turn the pinion P⁹, that will drive the spur-gear Q' of the turn-table Q. Should it then be desired to run the automobile from the turn-table, the chain C⁴ is unhooked and the said automobile can be run out of the entrance-opening A'.

It will be noted that I have described the apparatus so that the wheels of the automobile are driven by the driver-wheels S⁶; but it will be evident that if the clutch S² is thrown out of gear the power of the automobile can be used to drive the wheels C³ thereof on the said wheels S¹⁵ S⁶.

Having described my invention, I claim—

1. The combination with a vehicle; of means to produce on the occupants of the vehicle, the effect of running the vehicle while the latter is secured in place; means to produce an air-blast of varying temperature against the vehicle; a screen arranged to be visible by the occupants of the vehicle; and a picture-machine to represent pictures on the screen.

2. The combination with a vehicle; of means to produce on the occupants of the vehicle, the effect of running the vehicle while the latter is secured in place; moving screens adjacent to the vehicle; means to produce a hot-air blast against the vehicle; means to produce a cold-air blast against the vehicle; a screen arranged to be visible by the occupants of the vehicle; and a picture-machine to represent pictures on the latter screen.

3. The combination with a vehicle, of means to produce the effect of running said vehicle while remaining secured in place, and other means connected up with said means to turn the vehicle.

4. The combination with a vehicle, of means to produce the effect of running the vehicle while remaining secured in place, other means connected up with said means to turn the vehicle, moving screens adjacent to the vehicle, secondary means to produce an air-blast against the vehicle, a movable screen, and means for representing pictures on the latter screen.

5. The combination of a vehicle, a turn-table to carry said vehicle, driver-wheels on the turn-table to support the wheels of the vehicle, means to hold the vehicle on said driver-wheels, means to turn the latter wheels and thereby turn the wheels of the vehicle.

6. The combination of a vehicle, a turn-table to carry said vehicle, driver-wheels on the turn-table to support the wheels of the vehicle, means to hold the vehicle on said driver-wheels, means to turn the latter wheels, and means to turn the turn-table.

7. The combination of a vehicle, a turn-table to carry said vehicle, an engine, a shaft driven by said engine, a second shaft, a clutch

connected up between the shafts, a pair of driver-wheels driven by the second shaft, and the wheels of the vehicle arranged to be driven by said driver-wheels.

5 8. The combination of a vehicle, a turn-table to carry said vehicle, a line of shafting in two portions journaled under the platform of the turn-table, a clutch joining the said portions of the shafting, journal-bearings supported on the turn-table, an axle in said bearings, a bevel-gear on the axle meshing with a bevel-gear on the line of shafting, a pair of driver-wheels on the axle located to turn a pair of wheels of the vehicle, a brake-wheel 15 on the axle, a brake for the brake-wheel, and means to rotate the line of shafting.

9. The combination of a vehicle, a turn-table to carry said vehicle, an engine, a vertical shaft, connections between vertical shaft 20 and the engine, a horizontal shaft, a clutch connected up between the vertical and horizontal shafts, means to operate the clutch, an axle, driver-wheels on the axle to support and turn a pair of wheels of the vehicle, a brake-wheel on the axle, a strap-brake around the 25 brake-wheel, a brake-beam securing the ends of the brake-strap, a spring bearing up against

the said beam, a pin journaled in the other end of the brake-beam, a screw to move the free end of the brake-beam against said spring, and thereby tighten the strap on the brake-wheel. 30

10. The combination of a vehicle, a turn-table to carry said vehicle, an engine, means between the engine and turn-table to turn the latter, an axle journaled on the turn-table, a 35 pair of driver-wheels on the axle, a second driver-wheel adjacent to each driver-wheel and located in the same longitudinal direction, each driver and its adjacent wheel forming a support for a wheel of the vehicle, a second axle journaled on the turn-table, connections between the two axles, a pair of driver-wheels on the second axle, and a wheel adjacent and in the same longitudinal direction with the driver-wheels of the second axle to form 40 supports for wheels of the vehicle.

Signed at New York, in the county of New York and State of New York, this 29th day of November, A. D. 1904.
